Charles B. Bird,

Per W. A. Stevens Atty.

UNITED STATES PATENT OFFICE.

CHARLES BRAYTON BIRD, OF SIOUX CITY, IOWA.

SUSPENDERS.

SPECIFICATION forming part of Letters Patent No. 326,194, dated September 15, 1885.

Application filed January 28, 1885. (No model.)

To all whom it may concern:

Be it known that I, CHARLES BRAYTON BIRD, a citizen of the United States, residing at Sioux City, in the county of Woodbury, State of Iowa, have invented certain new and useful Improvements in Suspenders; and I hereby declare the following to be a full, clear, and exact description of the same.

My invention relates to the connecting medium between the strap and ends of the suspender; and it is the object of my invention to provide a cheap, durable, and convenient means for connecting the said parts and adjusting the same to each other.

15 To this end my invention consists, first, in a plate provided with slots to receive the strap of the suspender, and with slots arranged within the said slots for the strap of the suspender to receive the suspender-end.

20 In the drawings, Figure 1 is a rear elevation of a portion of the strap and end of a pair of suspenders connected together by my improved device. Fig. 2 is an elevation of a connecting-plate made in accordance with my 25 invention, provided with slots to receive the strap and end of the suspender.

A is a plate, preferably made of metal and of triangular form, provided toward each edge with slots B B' B², of sufficient length 30 and width to receive the strap of the suspender. The plate A is also provided with three slots, C, arranged in the outline of a triangle, located at the lower end of the plate in such manner that at least two of the 35 slots shall be wholly or in part between the slots B' B², and the third slot at or near the lower end of the slots B' B². By my preferred construction the slot B and one of the slots C will be parallel, while the other slots C 40 and the slots B' B² will diverge in opposite directions. The slots C are of length and width sufficient to receive the end of the suspender.

45 For the purpose of applying this plate, constructed as shown, to the joining of the strap and end of the suspender, the strap is passed through the slots B B' B² by entering the slot B, passing thence through the other slots and returning to the slot B, and the end is

passed through the slots C in the same manner as the strap is passed through the other slots.

This construction affords great advantages. The parts of the suspender may be securely connected to each other, and yet in case of 55 breaking of either part, or for other reason it may be desired to replace it, such part may be readily removed and replaced without disturbing the other. The size of the connecting medium is reduced to the very 60 lowest degree possible for the purpose of connecting the two parts, thus enabling a desirable economy in the cost of material, and hence the cost of the suspender, and, furthermore, avoiding the objections presented 65 by large or cumbersome connecting devices. It furthermore avoids the necessity for severing or sewing the strap or end, which is an important item in the cost of manufacturing 70 suspenders, and the main cause of their want of durability. Presenting as it does a flat surface, covered as it is by the textile material composing the suspender, the objection generally found to metallic connecting devices is entirely removed.

75 The device thus described may be used for attaching the strap to the front or back ends of the suspender.

As originally drawn, the present application described and illustrated, as well as the 80 invention herein described and claimed, a separate invention in an adjustable buckle. I do not claim that invention in this connection, however, it being my intention to file a 85 separate application for the same.

What I claim as new, and desire to secure by Letters Patent, is—

1. A device for connecting the strap and ends of a suspender, comprising a plate having slots B B' B² to receive the strap, and slots 90 C, arranged within or partly within the area of the slots B B' B², to receive the end, substantially as described.

2. The combination, with a suspender, of a slide consisting of a piece of sheet metal, 95 A, in the form of a triangle with rounded corners, and provided with one series of slots, B B' B², parallel to its edges, and with

another series of slots, C, partly within the contour of the first-mentioned three slots, as shown and described, whereby both the long and short straps of the suspender may be held by one slide in a single piece, and whereby the larger strap will partly cover the small strap to economize space, as set forth.

In testimony whereof I affix my signature in presence of two witnesses.

CHARLES BRAYTON BIRD.
